Spinning Fibrous Material.

Patented Oct 11, 1831.

6794X

Daniel Treadwell of Boston Mass.
Letters Patent dated Oct 11. 1831.

The Schedule, referred to in this Letter Patent and making part of the same containing a description in the words of the said Daniel Treadwell himself of his Improvement in the machine for spinning hemp, flax and other fibrous substances.

Be it known that the following is a true specification of an Invention made by me Daniel Treadwell of Boston in the Commonwealth of Massachusetts Engineer.

This invention is comprised in an improved machine, which I call a Spreey for spinning Hemp, Flax, and other fibrous substances. That the form, proportion and relations of every part of the machine may be understood I have hereto annexed, in several Figures, complete drawings of a machine arranged for operation which drawings are referred to in this specification and are hereby declared to form a part of the same.

Before proceeding to the description, it will be useful to state that spinning may be considered to consist of two operations first the drawing out of a filament

6794X

Oct 11, 1831

of the required fineness, from a mat of the fibrous material commonly in the state of a roving or roll and second, the twisting of the filament is drawn, which completes the formation of the thread or yarn. In some modes of spinning both of these operations are carried on at the same time in the same portion of the material that is the filament is elongated during the operation of twisting. In the invention herein described, the filament is drawn to the proper size before twisting it in any degree: and it will be hereafter seen that this improved machine or gypsey, consists of two distinct parts viz, the part represented in figures 1, 2, 3, 4 and 5 by which a small filament is drawn from a column or roving; this for the sake of distinction I call the drawing frame and the part represented in figures 14, 15 and 16 - this I call the bobbin frame. The drawings herein referred to, were reduced from and represent a machine for spinning rope yarns.

The size of the several parts of the drawings, is to that of the machine as three inches is to a foot. The scale under figure 5, is applicable to all the figures. Machines for fine threads or linen yarns are necessarily made smaller than that here given in proportion to the fineness of the thread or yarn required.

Figure 1 represents in elevation, a side view of the drawing frame. Fig. 2 represents a plan of that part of the same frame which is situated above the dotted line passing across fig 1. Fig. 3 is a section of the same frame, the part above the dotted line in fig 1 being removed. This figure is a plan. Fig. 4 is an elevation of the drawing frame as seen on the end when the filament is delivered from it. Fig 5 is an elevation as seen on the end where the hemp or roving enters the machine. Figures 6, 7, 8, 9, 10, 11, 12 and 13 are parts as seen detached from the machine. The same letters and signs are used to mark the same part as seen in any of the figures.

I shall now proceed to describe the drawing frame. A A A represent the wooden frame work of the drawing frame. Across the top of this frame pass two shafts supported in proper boxes to which B B. two pulleys are fixed and about which the hatchet belt C C. passes and by which it is carried. The belt is formed as follows: A number of the machine as shown in the drawings has 146 of rows of iron or steel points are made and riveted, or screwed firmly into iron plates called the hatchet plates see fig 6; each row contains 7 points. There is moreover at each end of every row of points, a pin having a head at its top. These pins are somewhat longer than the pins before fixing the pins to the hatchet plates a second plate of iron 2 fig 6 and fig 8.

6794X

Oct 11, 1831

293

pierced with nine holes at distances corresponding with the points and pins, is placed upon the points, the pins are then put in their place and riveted or otherwise fixed to the hatchet plate. This plate x is called the cleaver and ~~can~~ be moved freely up and down upon the points and pins, the pin heads preventing it from falling off or being removed; it is longer than the hatchet plate over which its ends project, one corner of the projecting part being cut out as seen in fig 8. A strap of leather or of strong webbing 3/4 inch wide & long enough to form a belt about the pulley $B.B'$ is pierced with holes in rows crosswise, each row having five holes at distances equal to those of the five middle pins fig 6. The distances of the cross rows from each other are $7/8$ inch and the holes do not form perfect rows lengthwise, but they are arranged as seen at the white spots C.C.C fig 2. The strap thus pierced is passed between the cleaver and the points, the cleaver being raised as seen fig 6, and the points are inserted in a row of holes; this operation is repeated until all the holes are filled and the strap is then passed down upon the hatchet plate. In passing the strap, the rows of points are turned so that the wide space between the first and second points fig 6 shall be to the right and left alternately, in the successive rows, the cleaver having been put on to the points so that the notches from the corners shall all be towards the same end of the strap. Another strap of like dimensions with this just described but not pierced is then taken and laid upon a table and the strap containing the rows of points is placed directly over it, the points being upwards. Two rivets are then fixed between every two rows of points through both straps or instead of the rivets the straps may be strongly sewed together through the spaces between the rows of points. The straps with the points thus fixed to them are then passed round the pulley $B.B'$ and the ends being fastened together they form the hatchet belt as seen at C fig 11. The hatchet belt is liable to stretch by use, the under pulley D is required to keep it to a proper tension. The shaft of the pulley D has its journals run in bearings which may be moved up and down to adjust it, as will be seen & understood from figs 1 and 2. To keep the hatchet belt evenly upon the pulleys $B.B'$ the guide fig 7 is fixed to the frame A A, the part E of the guide being downwards and the hatchet plate being between them. E fig 1 shows the end of the guide in its place. Two cast iron rails F F fig 1 and C are fixed parallel to each other upon the top of the wooden frame A A standing above it upon feet or pillars which are fixed to the frame. The distance between these rails is just equal to the length of the hatchet plates and their position such that the hatchet belt is between them. The end F of both rails is one quarter of an inch above the line of the top of the

6794x

Oct 11, 1831

pulleys B, B' while from $F' \text{ to } F$ the rails incline upwards so that the ends F' are one inch above that line and passing by the ends of the pulley B' at the right hand in fig 1. they turn down in a curve as seen in the figure. There is a projecting ledge on the inside of each rail about one inch wide running in the line of the tops of the pulleys B, B' . Upon these ledges the ends of the hatchet plates rest or slide, they therefore keep the hatchet belt straight. The ends of the cleavers which project over the hatchet plates, rest or slide upon the tops of the rails F, F, F' . Two curved plates of iron C, C' are fastened by the wooden blocks H, H to the frame A, A and are called the foreing plates. The figures 1, 2 and 5 will show the shape, place and position of these plates. The pillars J, J are fixed upon the rails F, F' and form bearings for the judgements of the pulleys J, J about which is passed the bobbin belt K, K . This belt is made of a number of small wooden cylinders, called bobbins. Every bobbin has a slot sawed into each of its ends. A number of bobbins are then laid parallel to each other at proper distances and straps are passed into the sawn slots and fixed there. When a sufficient number are in this way put on to the straps they are passed round the pulleys J, J and the ends of the straps are fastened and form the bobbin belt, as seen in the figures. A tin tunnel L is fixed between the foreing plates C, C' for the purpose of directing the roving, or sliver of hemp M into the hatchet belt. This tunnel runs in the direction of the dotted line between the foreing plates until it nearly meets the bobbin belt.

I have thus described that part of the drawing frame which holds or carries the hemp and from which it is drawn to form a filament.

I will next describe the apparatus by which it is drawn out. The roller N, N of each arm is fixed to the wooden frame A, A running across the top as seen in fig 4. They are fixed upon the top of the roller side, the four pillars O, O, P, P, O, O are similar to each other and the size, shape, and place of them will be seen in the figs 1, 2 and 4.

P, P which are likewise similar to each other but different from O, O are not seen distinctly in these figures. I have therefore marked their shape in fig 9. which is an elevation as they would be seen on fig 1. if they were not hidden by other parts. The levers Q, Q are hung by pins forming fulcrums or axes in the pillars T, T . These levers are connected together by the cord R . The bar R is that one cannot rise or fall without the other rises or falls with it. The steel rolled S, S called the drawing rollers are made to pass one the lower in the pillar P, P , and the other, the upper, in the lever Q, Q .

6794X

Oct 11, 1831

295.

fig 9 shows the holes which form boxes for the judgements of the rollers. The drawing rollers are coupled by the plates T T' to the shaft U running in the pillars O O, and connected by the gear wheels V V. The roller sill has a projection on one side passing towards the hatchet belt. A piece of iron W is fixed upon this projection and upon W is fixed the gatherer X.

This is made of plates of iron in nearly the form of an unequal four sided pyramid with its open base towards the hatchet points, and its truncated apex resting between the drawing rollers being shaped so as to conform to those portion of the rollers which are situated against it.

To prevent the end of the gatherer last described from being worn two pieces of steel plate are secured upon the inside of both sides being shaped to conform to the rollers as the sides of the gather are. The top of the gather passes off towards the bottom belt and a piece of thin or thin iron plate is bent over it, on each side and passes down nearly to touch the hatchet plates inside of the hatchet pins & outside of the hatchet points. This is called the tail of the gatherer and is seen at Y. The top of the gather has several slits cut through it so that the teeth of the comb 86 hereafter described can pass through it. There is moreover in the gather a false bottom hung by a joint at the end nearest the drawing rollers and capable of being sprung upwards like a trap door; this false bottom has slits across it corresponding with those through the top. Z is a fast pulley upon the shaft L to which the power is applied by means of a belt to drive the machine. A' is a loose pulley on the same shaft L on which the driving belt may run when the machine is at rest. On the end of the shaft L is the pinion C which drives the wheel d d' fixed on the shaft U which is coupled to the lower drawing roller S.

Let us now suppose a roving of hemp to be passed into the tunnel L and the pulley B to be turned in the direction of the arrow, the bobbins lying between the rows of hatchet teeth must be carried along with the hatchet belt, and as some of the bobbins by their connection in forming the bobbin pulley, constantly pass out of the hatchet belt at the right & others constantly pass into it on the left. When therefore the roving of hemp passed into the tunnel L meets the hatchet points it is passed into them by the bobbins and passes along in the hatchet belt until it arrives near the end F' of the rails F, F'. Now as the rails pass beyond the pulley B to the right, and as the cleavers see fig 6, as has been before described pass upon the top of the rail, it is evident that they will be passed upwards before the hatchet points and as the roving of the hemp is always above them, this also must be lifted out of those points. Suppose that the end of the roving is then passed through the gatherer X and that it is made to enter the drawing rollers. If the drawing rollers are now turned

Oct 11, 1831

faster than the hatched belt carrying the roving, the roving must be drawn out through the hatched points by the rollers forming a filament as much smaller than the original roving, as the rollers move faster than the hatched belt. If however the relative motion be constant then these proportions will be true only when the mean size of the filament is compared with the mean size of the roving, for the roving is not supposed to be of equal size throughout and moreover the ends of the fibres of hemp cannot be distributed at equal distances in it, hence more of these ends will be taken into the rollers together at some times than at others. Now when making ends meet the rollers together many fibres must be drawn out of the hatched together, and the filament be made larger than at other places, where the ends of fibres by being distributed in the roving at greater distances meet the rollers less frequently. To prevent as much as possible this inequality in the filament I use the apparatus now to be described, which will the regulator and the comb. A small cast iron frame c. c. 1 1/2" is fixed upon the wooden frame A A as seen in the drawing. The shaft f. f. is made to run on proper centres fixed in the frame c. c. and these are placed upon the wheels q, q'. The shaft f. f. with its connections is drawn separated from the frame at fig 10. These wheels are bored with a round hole and are capable of turning freely upon the shaft f. f. except as hereinafter described but are prevented by proper collars from slipping in the direction of the length of the shaft. Second shaft b. b. is made to run upon centres in the frame c. c. parallel to f. f. These are firmly fixed upon the shaft b. b. the wheels i, i'. The wheel q and i have 50 teeth each and the wheels q' and i' have 30 teeth each and the diameters of all the wheels are in proportion to the number of their teeth. The teeth of q play into those of i, and the teeth of q' play into those of i'. There are two locking pins o. o. which are fixed upon the wheels q, q' - b. b. are two clutch boxes placed upon the shaft f. f. These clutch boxes are free to slide in the direction of the axis of the shaft, but pins are fixed in the shaft which project into a groove cut lengthwise on the inside of each clutch box, so that the boxes cannot turn round upon the shaft. Several parallel grooves are turned into the body of each clutch box, and the clutch m. is connected with the clutch box b. by a movable joint which permits its outer end to fall back towards the middle of the clutch box, it is prevented however from falling back except on the application of a slight force by a steel spring which is fixed at one end to the clutch box while the other end projects upon the clutch m. There is a stop secured to the clutch box to prevent the spring from forcing the catch m. outward beyond a certain distance. A slide bar o. o. is placed in the frame c. c. parallel with the shafts f. f. and b. b. and is capable of being moved in the direction of its length, and in that direction only. Two

6794x

Oct 11, 1831

arms p. p. are screwed upon the top of this slide bar and pass from it towards the shaft f. f. and terminate directly over the clutch boxes dd', that is one arm over each clutch box. There is fixed to the under side of each arm p. p. a metal block or box q. q. which passes down to the clutch boxes. The under side of q. q. are formed in the shape of a portion of a hollow cylinder, and are ground so as to embrace the clutch boxes upon the grooves before described upon them through about one third of their circumference. (Fig 11. shows the slide bar o. o. and arms with the boxes q. q. separated from the other works. The figure represents the under side of these parts) A long shaft or axle r. r. is passes horizontally from under the slide bar o. o. to the right hand as seen in the drawings, until it projects beyond the frame A A. (In fig 11. this shaft is supposed to be broken off under the drawing rest S S and the left hand part is removed) A. A. r. is hung in centres which are fixed in the iron bearing s. s. This bearing is bolted to the frame A A. A. and prevented from springing by the iron brace b. d. The arm t passes horizontally from the right end of r. r. and the arm t rises vertically from its other end directly under the slide bar o. o. A stout springer, is fixed upon the shaft r. r. near its middle. This spring runs along on the side of the shaft and turns upwards against the side of the arm t until it reaches the top of t against which it poches with its whole elastic force. A connecting rod passes from a hook in the top of the springing u. b. another hook fixed in the under side of the slide bar o. o. - & is a bent lever (its fulcrum being a pin which passes through its middle and unites it to the bearing s. s. which is fixed to the frame A A. The vertical arm of the lever s is united at its top by a connecting rod with a hook which is fixed in the bottom of the slide bar and the horizontal arm of the same lever is united with the weight y. These hooks and connecting rods will be found in their places in fig 5 from the description, no letter of reference being thought necessary. (It will be seen in fig 1 that the shaft r. r. and the bearing s. s. are continuous in dotted lines behind a part of the frame A A - the spring on the weight y and some other parts will likewise be found, in dotted lines, in the same figure) From the arm t of the shaft r. r. there passes upwards the rod t. a. a (which is united with t by a movable joint) to the cross bar a. a. The rod a. a. passes through the middle of a. a. and receives a thumb nut upon its top. The connecting rod a. a. is a pass from the ends of the cross bar a. a. and are united by pins to the lever Q. Q. one rod uniting to each lever.

In addition to the parts hitherto described as connected with the shaft f. f. there is placed upon that shaft, the star wheel a. a. side view or elevation of which is given detached at fig 12. a. a. a. a. are plates of steel screwed upon the sides of the projecting points of the star wheel

Oct 11, 1831

and the breadth of these plates is greater than the thickness of the points of the wheel, so that they project over the sides of the points. The star wheel is fitted to the shaft f.f. like the wheels g.g. the shaft passing through a round hole in its centre, and proper collars are fitted to the shaft, on each side of it to prevent it from sliding in the direction of the length of the shaft. A wooden lever 6a is a paper from a point near the star wheel lying on tally the point directly under the gathering. A piece of brad is screwed upon the under side of this lever, near its middle, and a pin passes through this brad and through the cast iron pillars 7a. 7a which are fixed to the frame A A. This pin forms the fulcrum on which the lever turns. Two other pillars 8a. 8a, rise from the frame A A. on the sides of the lever 6a to prevent it from having any lateral motion. A small piece of steel ga which I call the bob is riveted to the end of the lever 6a by a pin passing through it near its middle, and likewise through two linkels standing out from a piece of brad 1 b fixed to the underside of the lever 6a. The lower end of the bob ga when the lever 6a is in the position shown in the drawing is in the horizontal plane of the centre of the shaft f.f. but so far from that shaft to the right, as seen in figs 1 and 3 that the projections of the star wheel h a are just capable of catching it and throwing it afterwards whenever the star wheel is turned round for the purpose.

A stop 2 b of iron is screwed upon the top of the lever 6a and a slight spring 3b tends to keep the top of the bob against the stop 2 b. A fast or click 4b having a lever end connected by a pin with the frame e.e. passes upwards through a hole or slot in the slide bar 5.5 by the side of the lever 6a. The click 4b can move on the pin which unites it with the frame e.e. with which it forms a hinge joint so that its top may describe an arc in the extension of the length of the slide bar. A spring is fixed to the frame 6d. (seen in dotted lines in fig 3) which acts against the click 4b and tends to press it against the lever 6a. so that whenever the end of that lever (at the left hand in figs 1 and 3) is raised above the top of the click, then the click slips under a piece of steel which is fixed upon the corner of the lever, where the click meets it and holds it up. But as will be hereafter seen it is required that the click should not remain under the lever except when the clutch bar 1 is carried by the slide bar 5.5, as near the star wheel that the catchbar is engaged against one of the plates 10a. Therefore to remove the click 4b from the lever 6a except in the case before stated a piece of iron constituting a stop is screwed over one side of the hole or slot in the slide bar, so that whenever the slide bar is moved so far to the right as seen in fig 3.

6794x

Oct 11, 1831

299

as to bring up the catch on' from the star wheel. that the stop above described shall prevent the side of the disk 1b opposite to that against which the spring acts and bending the spring disengage the disk from under the lever 5b is a weight upon the left arm of the lever 6a tending to depress the arm which it is attached. To the top of the lever 6a near its right end, as seen in fig 1 and 3 is riveted by a hinge joint the comb b. b. to each end of which are fixed rods q. b. which pass directly upwards through guide holes in the piece of cast iron W each side of the gatherer, and on the outside of the same and are fixed by their tops to the comb b. b. The comb is formed of several rows of iron or steel teeth riveted to an iron plate. the dots on the top of the plate in fig 2 show the number and place of the teeth. The several rows of teeth are directly over the slits in the top of the gatherer, which have been before described and on the application of a proper force to depress the comb, the teeth pass through these slits into the owing of lumps which is in the gatherer. Two cast iron pillars q. b. are fixed to the frame A. A. & c. and rise upwards above the lever 6a on each side of the same. A small lever 1c is placed between the pillars q. b. directly over the lever 6a and is hung upon a pin which passes through q. b. q. b. near their tops and through 1c. This pin forms a fulcrum or axis on which it turns. To the right end of 1c as seen in fig 1 and 3 there is connected by a movable joint, the rod 2c which passes directly upwards through guide holes in the piece of cast iron W and the bottom of the gatherer before described. The left end of the lever 1c as seen in fig 1 and 3. is connected with the lever 6a by hooks. It will be readily perceived by this description and the figures, that when the right end of the lever 6a is depressed the right end of 1c will be elevated and carry the rod 2c upwards, which will lift the false bottom before described of the gatherer the talk of the comb passing at the same time through the slits before described made in the false bottom of the gatherer upon the shaft b. b. is fixed the pulley 3c from which a belt passes to and over the pulley 5c fixed upon the shaft f. f. Upon the shaft h. h. is fixed the pulley 3c and from the pulley 3c a belt passes to and over the pulley 5c which is fixed upon the shaft 7c running in proper boxes in the upper part of the frame A. A. & c. The shaft 7c has the pinion 8c fixed upon it and this pinion drives a wheel 9c which is fixed upon the shaft 8d running in boxes upon the top of the frame A. A. parallel to 7c and carrying besides the wheel 9c the pinion 9d. The pinion 9d drives the wheel 3d which is fixed upon the shaft of the pulley B. To understand the operation of the regulator the comb

Oct 11, 1831

and other apparatus connected with and necessary to it, let us suppose the ring of hemp to have been passed through the tunnel I and along the hatched belt and its end to be between the drawing rollers $S.S.$ as has been before described. Let us also suppose that a constant rotary motion be given to the rollers $S.S.$ in the direction required for drawing out the filament through their connexion by the shafts which join $S.S.$ which had been before diverted with the pulley a which is driven by a belt carried by a very sufficient power. The motion from the pulley a will likewise be communicated to the pulley b and from thence through the belt passing from $S.S.$ to b by which the shaft $f.f.$ must also be turned upwards moreover that the thumb nut upon the top of the rod $1a$ has been so fixed that when the filament between the rollers $S.S.$ is of the required size the catches $m.m.$ shall all be disengaged.

In this state of things the motion of the shaft $f.f.$ will not be communicated to the wheels $g.g.$ nor to the star wheel $4a$ but they will all remain at rest, with the shaft $f.f.$ standing in them as the hatched belt is under the condition stationary. The ring is not advanced to the drawing rollers, and it must therefore soon happen that the filament will become too small as soon as this is the case in a small degree, the upper drawing roller which rests upon and is supported by the filament beneath it, must fall, and the ends of the levers $Q.Q.$ which project from the rollers to the right in fig 1 and 2 must be depressed and the rods $3a$ with the cross bar $2a$ and the rod $1a$ likewise, must drop downwards. Now the weight y , acting through the lever $v.v.$ on the slide bar $o.o.$ tends naturally to draw the slide bar to the right as seen in fig 5, but this tendency is ordinarily resisted by the counterpoise of the slide bar with the spring $u.u.$ fixed upon the shaft $1,1$, the horizontal arm b of which shaft is united by a joint with the rod 1 . When however the rod $1a$ goes downwards the arm b is no longer supported, cannot keep the shaft $1,1$, and the spring $u.u.$ in their former position, but its sufficient weight carries the slide bar to the right, the slide bar carrying with it the top of the spring $u.u.$ which at the same time as the shaft $1,1$ disengages the arm b .

When the slide bar $o.o.$ moves as herein described to the right it carries the bars $g.g.$ and likewise the clutch boxes $1,1'$ with it. The clutch boxes are by reason of the connexion with the shaft $f.f.$ as before described always maintained to revolve with the shaft $f.f.$ and the catches $m.m.$ and $n.n.$ are of course carried round with them. If therefore the clutch boxes are carried far enough to the right as seen in fig 5, the catches $m.m.$ and $n.n.$ would strike the pins $k.k.$ and $l.l.$ respectively, but as the pin k is larger than l and approaches more nearly to the circle described by $o.o.$ than the pin l approaches that described by $m.m.$ the action of the slide engages $m.m.$

6794x

Oct 11, 1831

301.

against k' before m . can strike k . It will beat me perceive that as soon as m is engaged against k the wheel g will be made to revolve. this will drive the wheel i , by which the pulley $5^{\circ}e$ must revolve, and the motion of $5^{\circ}e$ will be communicated by its belt to the pulley $6^{\circ}e$ and from thence through the pinion $6^{\circ}e$ the wheel $g^{\circ}e$, the pinion $2^{\circ}d$, and the wheel $3^{\circ}d$ the pulley B by the revolution of which the hatchet belt will be moved and the roving advanced towards the drawing roller $5^{\circ}S$ with a certain velocity which will be found by measuring the several pulley, wheels and pinions which are concerned in communicating and multiplying the motion. If by the advance of the roving with the velocity thus obtained as only fibres of hemp are presented to the drawing roller as are required to increase the filament to its proper size, then the upper drawing roller is raised by the filament thus increased and the slide bar $o.o$ by reason of its connexion with the upper roller (through the connecting rod and hooks, the spring in the shaft r,r , the arm t , the rod l & the cross bar $2^{\circ}a$, the rods $3^{\circ}a$ and the lever $Q.Q$) will be carried to the left as seen in fig 5 and the clutch boxes will be moved with it, by which the catch m , will be disengaged from the pin k , when the wheel g , and the several pulley and wheels and pinions by which it gave to the pulley B must come to a state of rest and the further advance of the roving to the drawing roller will cease.

Let us suppose however that when m and k are engaged and the roving advancing as heretofore described, the size of the filament does not increase, but that from the smallness of the roving, the fibres are presented to the drawing roller so infrequently that the filament diminishes yet more in size. In this case the upper roller will continue to fall and the slide $o.o$ connected with it by the apparatus before described, will continue to move to the right as seen in fig 5, until the catch m engages the pin k' upon the wheel g' and carries it round with it. when it will be seen that the wheel g' is larger than the wheel g , while the wheel i' is smaller than the wheel i , in this new connexion, therefore the shaft b and the pulley $5^{\circ}e$ will be driven faster than they were when their motion was derived from the wheel g , and the greatest velocity of the pulley $5^{\circ}e$ being communicated by the belt pulley, wheel, and pinions as has been before described to the hatchet belt the roving of hemp must be advanced more rapidly to the drawing roller $5^{\circ}S$ and by this the filament receives a greater accession of fibres in a given time. When by this accession of fibres the filament is increased to the proper size the upper roller will rise and the clutch boxes will be carried to the left, the catch m being disengaged from the pin k' and the hatchet belt and roving will rest.

It will be seen that while the wheel i' is driven by the wheel g' the wheel g must be driven by the wheel i , in this state of things the pin k will make more

6794X

Oct 11, 1831

revolutions in a given time than the catch m and as they come in contact with each other it is necessary that m should pass n without a permanent locking. Now when k strikes m in this way the contact is upon the sides opposite to those which were struck when k was driven by n , and to let them pass each other the sides or corners of both m and k which would otherwise catch and interrupt the motion are taken off and the end of the pin and the edge of the catch from inclined planes which sliding upon each other the catch is forced backwards against the resistance of the spring hitherto described, and thus k passes by m ; the spring always causing m to return to its former position after k has passed it. Figure 15 shows the form of m and k . 4d. 4d are the faces which strike when k is driven by n , and 5d. 5d are the inclined planes which meet when the wheel g is driven by the wheel k .

Let us now consider the operation when the filament is too large. Suppose that the advancement of the roving, as before described, brings so great a number of the ends of fibre in contact with the drawing roller that the filament not only attains a sufficient size but becomes too large. In this case the upper roller supported upon the filament is elevated above its ordinary place, and by means of the conical pins before described the arm t is carried upwards, the shaft r rolling back, the top of the spring e is carried to the left and the slide c & c and the click boxes also, from their positions before described must be carried to the left. This brings the face of the catch m into contact with the projectors of one of the plates $5a$, and from this engagement the star wheel $6a$ is made to revolve with the shaft f . As soon as this revolution commences, one of the plates $5a$ upon one of the points of the star wheel must strike the bob $9a$, and throw the end of the lever $6a$, to which it is attached, upwards which will be caught and held by the fall or click u . The length of the fall or click u is such that it catches the lever $6a$ when it is carried to the highest point that it can be carried by the star wheel, consequently when it is so caught the point of the star wheel do not by their continued revolution strike with much force if they strike at all upon the bob. It will be once perceived by an inspection of the drawings that when the left end of the lever $6a$ to which the bob is attached, is thrown upwards the right end must be depressed, and the comb $7b$ be carried downwards at the same time the right end of the lever $6a$ is sent from the comb of that lever as before described with the lever $6a$ to carry upwards and its motion being communicated by the rod $2c$ to the false bob $8a$ the gather that will be carried upwards. The motion of the comb and of the false bottom of the gather will cause the teeth of the comb to be passed into the bottom of

6794X

303

roving, which is in the gatherer. This will prevent the fraying of the fibres of which the roving is made up, to the drawing rollers while some of the fibres, the ends of which are already in the drawing rollers, will be broken off and thus the size of the filament will be speedily reduced to its proper dimensions. It may happen on the passage of a lock of tow or a knot of entangled fibres through the rollers, that they will be separated to a considerable distance. In this case when the clutch boxes on the shaft ff are brought against the collar of the wheels g and g a, so that the slide o o cannot pass any further to the left, the spring u, yields as the arm t rises on the separation of the rollers and as soon as the tow or other matter has passed and the upper roller falls, the spring u, returns, by its elasticity to its former state. When the filament has been reduced to the proper size the upper roller must consequently fall to the place which that size of filament determines. This motion being communicated to and modified by the various parts connecting the upper roller with the slide o o as heretofore described, the slide bar must move to the right, as seen in fig 5 and the fall or click 4 b, being by the action of the stop fixed as heretofore described upon the top of the slide bar carried from under the corner of the lever b a the weight 5 b will cause the arm of the lever to which it is attached to fall, by which the comb will be raised and the false bottom of the gatherer will be depressed and thus no further interruption be offered to the passage of the roving to the drawing rollers.

In one barley the drawing frame remaining to be described are the cone pulley 7 d, upon the shaft b, the shaft 1 d and the pulley 9 d and 8 e upon the same; and the spring guide 2 e 2 e 2 e. But as these parts are connected in their use with the bobbin frame, I shall notice them as may be necessary hereafter.

Having thus described the construction and mode of operation of the principal parts of the drawing frame I shall proceed to describe the second part of the machinery, viz the bobbin frame by which the filament is twisted and wound up.

Figure 14 represents an elevation of this frame in its position connected with the drawing frame. Fig 15 is a plan of the bobbin frame and Fig 16. an elevation as seen in the end next the drawing frame. Figs 17 and 18 may appear as continuations of Figs 1 and 2. I have however marked them as distinct figures in accordance with the division adopted for describing the whole machine. The wooden frame of the bobbin frame is presented at 6 e 6 e 6 e 7 e. of this, over its bottom passes the shaft 7 e having its ends placed in proper boxes upon the frame 6 e 6 e 8 e. Upon the shaft 7 e is

6794X

Oct 11, 1831

fixed the cone pulley 82. which is driven by a corded belt running from the cone pulley 7d upon the drawing frame. There is moreover upon the shaft of the latter gear wheel 7e the flyer is shown at fig. 14 to its guides, both of which are hollow running in proper boxes in the frame 62. 62. 23. 23. are shears or pulley over which the yarn runs to be wound upon the bobbin. The bobbin spindle 3f runs in a box upon the frame 62. 62. and in a bar marked 4f which is placed upon the back of the flyer and passes from one side to the other of the same and is capable of sliding upon the bars in the direction of their length. It will be understood that the spindle passes through the hollow centre of the right guides of the flyer. At fig. 14, the hole through the guides being somewhat larger than the spindle. 5f is the bobbin placed upon the spindle and kept in place by a pin which passes through an ear or small piece of wood which is fixed to the bobbin and likewise through the spindle.

The pulley 6f is fixed to the bobbin spindle and the pulley 7f is fixed to the flyer. The drum of 8f has its guides placed in proper boxes fixed to the frame 62. 62. The level wheel 1g is fixed upon the shaft of this drum and being driven by the level wheel 9e causes the drum to revolve. A belt passes from the drum 9f to the pulley 6f and another belt from the same down to the pulley 7f. The broader pulley 2g rests upon the belt which passes from the drum to the pulley 6f, for the purpose of keeping that belt at a proper degree of tension, which may be regulated by weights placed upon the frame in which the pulley revolves which frame as will be seen in the figures, is hung by guides which move in the frame 62. 62. 23.

From what has now been specified it will be seen that motion being given as heretofore described, to the drawing frame, such motion must be communicated from the pulley 7d on that frame, by the belt to the pulley 8e on the bobbin frame and from thence, by the level wheels 9e and 1g. to the drum 9f. It must moreover, be evident that the pulleys 6f. and 7f. will at the same time be made to revolve as they are connected by belt with the drum 9f. The filament therefore as delivered from the drawing rollers, being passed through the hollow guides in the left end of the flyer fig. 14 and over the pulley 2f. 2f. to the bobbin to which its end is fastened, must be, by the revolution of the flyer and bobbin, be limited. In order however that it may be wound upon the bobbin it is necessary that the bobbin and flyer should not make an equal number of revolutions in an equal time.

Now it will be seen that the end of the drum g from which the belt passes to the pulley 6 is larger than the other part of the same drum while the pulley 6 and 7 are nearly equal in size.

Hence the flyer will make a greater number of revolutions in a given time than the bobbin. The tendency therefore will be to wind up the yarn upon the bobbin with a celerity proportional to the difference between the speed of the bobbin and that of the flyer, that is whenever the flyer shall have passed through one revolution more than the bobbin, then one turn of yarn must be wound upon the bobbin. But the bobbin increases in size as the yarn is wound upon it and consequently the turns of yarn as the circumference of the bobbin increases become larger. It is necessary therefore that as the bobbin fills, it should approach more nearly in its revolutions to those made by the flyer. Now the flyer is driven with a uniform velocity and the filament also is derived from the drawing rollers with a uniform velocity. Suppose then that the circumference of the bobbin when naked be one foot and that the surface of the drawing rollers advances through one foot in two seconds, and that the flyer makes twenty revolutions in two seconds then that the yarn may be wound up; the bobbin must make nineteen revolutions in two seconds; when however the bobbin by being filled with yarn, has a circumference of two feet it is evident that it must make nineteen and a half revolutions in two seconds that the same object may be accomplished, the velocities of the drawing rollers and the flyer remaining constant. To provide for the required increase of velocity in the bobbin it is only necessary that the belt which passes from the drum g to the pulley 6 shall be of a slight tension that it may be ~~that it may not~~ made to slip in some degree by the pulling of the yarn itself upon the bobbin from the constant tendency by the flyer to wind it up.

For the purpose of spreading the yarn over the whole surface of the bobbin it is necessary that the bobbin should be moved alternately through a space equal to its length in the direction of its axis. To accomplish this a collar is placed upon the spindle at $3q$. This collar runs in a slot $4q$ which stands upon the slide $5q$ which slide can be moved in the direction of its length its right end resting in a proper box on the frame $6e$.

Two chains or straps pass from buckles on the slides $5q$ seen in fig 14, over the top of the pulley $6q$ in opposite directions and are fastened

6794X

Oct 11, 1831

to the periphery of the pulley on different sides of the same. Two other chains or straps similar to those above described pass from buckle on the slide or rod 7g and are connected with the small pulley 8g. The pulley 6g and 8g, are upon the same shaft 9g the peripheries of which run in opposite directions in the frame 6c. It will be understood that the arrangement of chains or straps connecting the slide 5g with the pulley 6g and the slide or rod 7g with the pulley 8g is similar to that often used for moving the pistons of pumps or fire engines. Upon the shaft 1h which runs in proper boxes in the frame 6c is fixed the heart wheel 2h. Two pins 3h 5h are fixed to the slide or rod 7g so that their sides are in contact with the heart wheel on opposite sides of the same. Upon the shaft 1h is fixed the pulley 10h from which a belt passes to the pulley 5h upon the shaft 6h. Upon the same shaft 6h is fixed the pulley 7h from which a belt passes to the pulley 8h upon the shaft 9h, upon which shaft 9h is fixed the pulley 1h. The shafts 6h and 9h run in boxes fixed to the frame 6c 6e. The pulley 8h is connected by a belt with the pulley 10h both of which are referred to upon the drawing frame. It will be seen that there is upon the same shaft with 10h the pulley 9d. From this pulley 9d, a belt passes to and round the shaft 10.

To understand the effect of the parts last described in going on, suppose the shaft 10 of the driving frame to revolve, its motion will be communicated by the belt to the pulley 9d which will turn the pulley 10 upon the same shaft shaft with it. The rotation of 10 will give motion to 8h whence as will be at once perceived the pulleys 8h, 7h, 5h and 3h together with the heart wheel 2h by reason of their connection as heretofore described must all revolve.

The revolution of the heart wheel gives a rectilinear alternating motion to the rod or slide 7g. This rod or slide from its connection with the pulley 8h communicates a circular alternating motion to that pulley, which motion must likewise be communicated to the pulley 6g, and 6g must communicate by reason of the connection as heretofore described a rectilinear alternating motion to the slide 5g. It is evident that the motion of 5g will be communicated to the spindle 3f, the bobbin 5f, the pulley 6f and the bar 4f, which forms one of the boxes in which the spindle revolves. The belt which passes from the pulley 6f to the drum 9f will during this circular or rectilinear alternating motion of the bobbin pass along over the top of the drum 9f and the hinder pulley 2g.

There remains to be described only the apparatus by which the motion of

6794x

Oct 11, 1831

507

the machine is destroyed, whenever the thread or yarn is from any cause broken. The first part of this is called the stopping guide and is seen on the drawing frame marked 2. c. fig 1 and 2. It is a cord of iron hung by a hinge joint at one end, to the frame A A 2. a. From 1. end which forms the joint the cord passes horizontally towards the bobbin frame, when it reaches nearly to that frame, it is bent so as to pass directly under the filament or yarn, where it is to, i.e. the operation of twisting, from this it is again bent upwards so that it forms a sort of hook, which lies against the side of the yarn as seen in fig 1.

Upon one side of the cord thus described, is swivelled a piece of iron for making a small cord as seen in fig 2, and through this fork as here seen, the main belt against the machine is drawn pass from a drum above to the pulley a. To the end of the stopping guide next to the bobbin frame is fixed a cord which passes from it to and over the sheave or pulley 2. placed upon the bobbin frame, seen at fig 16. and to the end of this cord a small weight is attached.

To understand the operation of this apparatus, let us suppose the main belt to be running upon the fixed pulley a by which the machine must be kept in motion. Under this condition if the yarn be coming and whole, and attached to the bobbin it will be drawn in a right line from the drawing rollers to the axis of the flyer. At the same time the weight attached to the cord which passes from the stopping guide, as before described, tends constantly to draw the end of the stopping guide towards the pulley a, but as the end of the stopping guide, passes upwards by the side of the yarn, it cannot move toward the pulley 2. without carrying the yarn before it, and in this it is resisted by the whole tension of the yarn. Under these conditions therefore the main belt will continue to run on the pulley a. When however the yarn breaks, the force which kept the stopping guide in its place is destroyed, and it is moved at once by the action of the weight upon the cord as before described, toward the pulley 2. and by this motion, the main belt is carried by the fixed guide before described on to the loose pulley a' and consequently the motion of the machine will no longer be maintained.

The particular form of stopping guide here described is suited to a flyers which is driven by a belt passing from a drum placed above it. Some modification of form will be required to suit it to a belt passing to it in another direction. But this and other modifications of form such as adapting it to a shuttlebox instead of a belt, it is not an essential alteration as they are not changes of character or principle in the apparatus.

Oct 11, 1831

It has been necessary in the preceding specification to describe a great many mechanical instruments which are in common use in various machines. This has been done that their application in this machine might be understood, and without intending to advance any claim to have invented them. Thus levers, wheels, pinions, clutch boxes, belts, pulleys, rollers, shafts, hatched points, flyards, spindles and many other instruments, not necessary to my invention, are the common property of mechanics and I make no claim to have invented any of them, either generally or in particular forms and proportions in which I have described them. Again I have in this machine used many simple combinations of these instruments which are not of any invention, such as combining wheels with pinions, belts with pulleys, clutch boxes with shafts, and other like relations, which need not be named as exceptions to my invention as I shall proceed to state definitely, that which I have invented.

First then I have invented the combination of plates, points, pins, cleats, caps &c as herein described which forms the hatched belt, which I have, combined with the pulley, rail, and framing plate, the whole forming the apparatus from which the hemp, flax or other fibrous substance is drawn out.

Second I have invented the combination of instruments which constitutes the regulator, as herein described together with the apparatus connecting it, 1st with the pinion cover of the machine & 2nd with the levers in which the upper roller revolves - and 3rd with the hatched belt, as herein described.

In using the words "as herein described" I do not mean to limit my invention to the specific form in which the regulator and connecting apparatus are constructed for it is obvious that many changes may be made in them without affecting them in principle or character. Thus by way of illustration, pulleys, and belts may be used instead of gear wheels, springs may be substituted for weights &c or the same parts may be used under great varieties of form, position, and mode of connection, and yet the character of the invention remain unaltered.

Third I have invented the combination of the end and apparatus by which it is operated upon, in the relations and under the conditions as herein described. I do not intend in this any more than in the preceding summary, to limit my claim for letters patent to the specific form of combination and connecting apparatus described but I declare that I am the original inventor of the combination of which the description heretofore given indicates the character.

Fourth. I have invented the combination of the stopping guide and weight with the thread or yarn as the same is formed by the machine, by which the machine is taught

6794x

Oct 11, 1831

309

to rest whenever the unity of the thread is destroyed. In this also I declare myself the inventor of the combination of which the particular description heretofore given, points out the character without intending to limit the invention to the specific form of apparatus denoted.

Under the four preceding heads I have stated, summarily the substance of my invention, and I do not herein claim Letters Patent as the inventor of any parts or combinations not included in them however such parts or combinations may have been described in the foregoing specification or shown in the drawings referred to therfrom.

In testimony that the above is a true specification of my said invention I have hereunto set my hand this first day of September in the year of our Lord, eighteen hundred and thirty one
